UNITED STATES PATENT OFFICE.

JOHN BIZON, OF WYANDOTTE, MICHIGAN.

BAYONET AND WIRE-CUTTER.

1,287,569.

Specification of Letters Patent. Patented Dec. 10, 1918.

Application filed September 10, 1918. Serial No. 253,389.

To all whom it may concern:

Be it known that I, JOHN BIZON, a citizen of Poland, residing at Wyandotte, county of Wayne, and State of Michigan, have invented certain new and useful Improvements in Bayonets and Wire-Cutters, of which the following is a specification.

This invention relates to improvements in implements of warfare and particularly to types known as bayonets adapted to be used in connection with rifles.

The principal object of the invention is to combine with a conventional type of bayonet, a wire cutting device by means of which strands of wire, formed into entanglements and fences may be readily severed.

A further object is to provide such means, so combined with the hilt or shank of a bayonet as to present no objectionable appearance and which is easily operated.

These and other like objects are attained by the novel construction and combination of parts hereinafter described and shown in the accompanying drawings, forming a material part of this disclosure, and in which—

Figure 1 is a side elevational view showing a conventional type of bayonet having an embodiment of the invention combined with the handle.

Fig. 2 is a front view of the same.

Fig. 3 is a fragmentary vertical sectional view taken on line 3—3 of Fig. 2.

Fig. 4 is another side elevational view looking from the interior of the opposite handle element.

Fig. 5 is a transverse sectional view taken substantially on line 5—5 of Fig. 3.

Fig. 6 is another transverse sectional view taken on line 6—6 of Fig. 3.

Fig. 7 is a fragmentary perspective view, looking from the inner side and lower end of the wire cutting lever, and

Fig. 8 is a perspective view, showing one of the wire cutting elements.

In the drawing the numeral 10, designates the main or body portion of the handle, with which is engaged a ferrule 11, having an extending open eye or loop 12, engageable with the barrel of the rifle and extending beyond the ferrule is a double edge blade 14, terminating in an acute sharp point 15.

Formed longitudinally in the butt 18, of the handle is an under-cut groove or recess 19, adapted to engage with keepers set in the rifle barrel, so that the handle of the

bayonet may be firmly affixed thereto in the ordinary manner, this butt is integrally formed with the shank 20, extending rearward from the blade 14 the entire length of 60 the handle, and in which is a notch 21, receptive of the wire to be cut.

A raised curved boss 22, extends upward from the shank 20, adjacent to similar raised bosses 23, and 30 formed with rigid parts of 65 the handle and through which passes a pivot pin 25, the side elements 27 and 28 of the handle, being further held to the central stem or shank 20, by fixed rivets 29, the combined sides extending lengthwise between 70 the collar or ferrule 11, and the end enlargement or butt 18.

Pivoted between the bosses 22 and 30, on the pin 25, is a plate lever having an outer curved portion 32 and a cam-like raised 75 edge 33, extending outward, while extending in the opposite direction is a flat brace element 35, formed with a hollow cover 36, shaped to conform with the handle 10, and having an undercut recess 37 in the bottom 80 38, with which is engageable a projection 40, formed with a block 41, and actuated by the extending knob 43, a flat spring 42, engaging upon either side of an angular detent 45, formed with the base of the sliding block 41, 85 which operates in a recess 46 in the outer portion of the butt 18.

A sliding shear plate 48, is guided in a recess 49, formed in the handle, while at the bottom of the recess is a longitudinal slot 50, 90 engageable with a spline or key 51, formed at the bottom of the shear blade 48, so it is guided laterally. The shear blade is formed with a beveled cutting edge 52, while upon the opposite side is an extending finger 54, 95 normally pressed downward by a coiled compression spring 55, causing the cutter blade to be held frictionally against the cam 33, of the actuating lever 36.

From the foregoing it will be seen that a 100 neat and effective implement for cutting wire has been disclosed and that the same is conveniently combined with a bayonet or like implement, the use of one being possible without interfering in any manner with the 105 use of the other.

Having thus described my invention what I claim as new and desire to secure by Letters Patent, is—

1. In an implement of the class described, 110 the combination with a knife blade, and a handle rigidly engaged therewith, of a fixed

shear blade attached in said handle adjacent to said knife blade, a movable shear blade slidably arranged in said handle, a lever pivoted in said handle, a cam formed with said lever adapted to contact with said movable shear blade, and a spring fixed in said handle adapted to retract said movable shear blade when said lever is in a raised position.

2. In an implement of the class described, the combination with a knife blade and a handle permanently engaged therewith, said handle having a longitudinal recess upon one side, of a fixed shear blade secured in said handle adjacent to said knife blade, a movable shear blade slidably engaged in said handle, a lever pivoted in said handle and adapted to form a part thereof when in a closed position, means for normally holding said lever in close engagement with said handle, and a cam formed with said lever

adapted to actuate said movable shear blade into operative position.

3. In an implement of the class described, the combination with a bayonet comprising a knife and a handle permanently engaged therewith, of a lever pivoted in said handle and forming a part thereof, means for normally holding said lever in intimate engagement with said handle, a fixed shear blade set in said handle adjacent to the knife, a sliding shear blade arranged in said handle and adapted to be operated by said lever, a detent movable in said handle engageable with the free end of said lever, means for operating said detent, and means for holding said detent in either of its adjusted positions.

In testimony whereof I have affixed my signature.

JOHN BIZON.
